United States Patent Office

Des. 178,700
Patented Sept. 4, 1956

178,700

SHOE OR SIMILAR ARTICLE

Jack Sandler, Boston, Mass.

Application January 3, 1956, Serial No. 39,555

Term of patent 7 years

(Cl. D7—7)

Fig. 1 is a front perspective view of a shoe or similar article showing my new design.

Fig. 2 is a front perspective view illustrating the strap portion removed from the rest of shoe.

I claim:

The ornamental design for a shoe or similar article, substantially as shown.
